PRINTING MACHINE

Walter T. Gollwitzer, Chicago, Ill., assignor to
Addressograph Company, Wilmington, Del., a
corporation of Delaware

Original application July 23, 1930, Serial No.
469,953. Divided and this application Decem-
ber 5, 1931, Serial No. 579,203

24 Claims. (Cl. 101—57)

This is a division of my application, Serial No. 469,953, filed July 23, 1930.

This invention relates to printing machines of the kind wherein a plurality of printing devices are introduced into a magazine and from which they are withdrawn and fed through printing position, whereat impressions are made therefrom, and then to a galley wherein the printing devices are collected in the same sequence as that in which they were arranged when introduced into the magazine whereby the collected printing devices may be removed from the galley and stored in drawers of storage cabinets until they are to be used again.

15 The printing machines are ordinarily so arranged that the printing devices move therethrough in a step-by-step manner and an impression is made from the printing device at printing position during an at rest interval in the step-by-step movement. Not all of the printing devices moved through printing position are always used in a printing operation and a selector mechanism, which cooperates with identifying means on the printing devices, determines which 20 of the printing devices are to be used in a printing operation. Often it is desired to make more than one impression from the printing devices from which impressions are being made and to this end the step-by-step movement of the printing devices is interrupted while the platen of the machine is making the desired number of impressions after which the step-by-step movement of the printing devices is resumed.

Among the objects of my invention are to interrupt, in a novel way, the step-by-step movement of the printing devices either manually or automatically; to provide an adjustment whereby a determined number of impressions may be made from the printing devices, that is to say, so that 25 either one, two, or more impressions may be made from a printing device; to interrupt operation of the selector mechanism while multiplicate impressions are being made from a printing device and to render the selector operative as the last 30 of the multiplicate impressions is being made; to constantly operate the driving device for imparting a step-by-step movement to the printing devices but to provide a portion separable from the constantly driven device so that the step-by- 35 step movement of the printing devices is interrupted without altering the constant operation of said driving device; and to provide for multiplication by a simple and economical construction of efficient and positive operation and which 40 may be readily installed in printing machines of

various designs without requiring extensive alterations therein.

In the selected embodiment of the invention illustrated in the accompanying drawings

Fig. 1 is a fragmentary front elevation of a printing machine embodying my invention and in which certain parts are shown in section;

Fig. 2 is a transverse sectional view of the printing machine as illustrated in Fig. 1;

Fig. 3 is a plan sectional view taken substantially on the line 3—3 on Fig. 4;

Fig. 4 is a fragmentary rear elevation;

Fig. 5 is a sectional view taken substantially on the line 5—5 on Fig. 4;

Fig. 6 is a fragmentary detail view of a shifting mechanism; and

Fig. 7 is a fragmentary detail view of a portion of the controlling device forming the subject matter of this invention.

I have illustrated my invention in association with a printing machine embodying a jack shaft 8 having a pulley arrangement 9 or other suitable power receiving device fast thereon to which movement is imparted from a suitable source of power such as an electric motor (not shown). On the jack shaft 8 is a pinion 10 meshed with a spur gear 11 rotatable on the main drive shaft 12. A controlling rod 13 is provided for engaging the clutch 14 to connect the spur gear 11 to the shaft 12 whereby movement imparted to the pulley 9 will be transmitted through jack shaft 8, pinion 10, spur gear 11 and clutch 14 to said drive shaft 12. The jack shaft 8 and the drive shaft 12 are journaled in suitable bearings in the frame 15. The table or bed 16 of the machine is mounted at the upper end of this frame. At one side of the machine and carried by the bed 16 is a magazine M into which printing devices D are introduced and from which the printing devices are successively withdrawn and fed to printing position above an anvil whereat impressions are made therefrom by the platen P through a suitable ink ribbon (not shown). The platen P is mounted at the lower end of the housing 17 at the outer end of the platen arm 18 pivotal about the shaft 19 carried by the frame of the machine. Formed as an extension of the platen arm 18 is an arm 20 which depends below the shaft 19. At the lower end of the arm 20 is a half-round lug 21. An arm 22 is pivotally mounted at 23 on a bracket 24 depending from the bed 16. A notch 25 is provided in the upper edge of the arm 22 and the lug 21 seats in this notch to latch the platen in its upper or non-printing position, as shown and described in my

co-pending application, Serial No. 572,489, filed November 2, 1931.

In my co-pending application, Serial No. 469,953, filed July 23, 1930, I have described a selector mechanism for controlling the operation of the platen from the printing devices. This selector mechanism includes a head H wherein a plurality of detecting fingers F are mounted and which are positioned by engagement with identifying characteristics on the printing devices. When the fingers are positioned they cooperate with a matrix to regulate the positioning of the arm 26 which, in turn, regulates the positioning of the arm 27 which has an upstanding portion 28 at the free end thereof on which there is a triangularly shaped lug 29. Pivotedly mounted at 23 is a vertically extending arm 30 having a notch 31 therein and a formed end portion 32. A triangular portion 33 is defined between the notch 31 and the forward end 32 and the apex thereof lies in the plane of the front edge 34 of the portion of the arm 30 below the notch 31. Whenever the arm 26 is so positioned that the upwardly extending portion 28 of the arm 27 is so located that the triangularly shaped lug 29 seats on either the edge 34 or the apex of the projection 33, the arm 30 is pivoted into the position shown in Fig. 2 and the arm 35, connected to the arm 30, is also pivoted. A spring 36 extends between the arms 22 and 35 and when the arm 35 is pivoted as described, the spring 36 is tensioned whereby the arm 22 is moved downwardly and the notch 25 is retracted from engagement with the lug 21 whereupon the arm 18 is free to pivot about the shaft 19 so that the platen P will move toward printing position. Should the triangularly shaped portion 29 be positioned in either the notch 31 or along the formed end 32, the spring 37 will act on the arm 22 to pivot it into an upper position whereat the lug 21 will seat in the notch 25 to latch the platen in its upper or non-printing position. When the platen arm is released in the manner described so that the platen may move toward printing position, impression pressure will be imparted to the arm at the time the platen moves into a predetermined position. To regulate the time at which impression pressure will be imparted to the platen, I provide an arm 38 having a cam surface 39 thereon. A dog 40 is pivotally mounted at 41 on the arm 20 and the nose 42 of this dog travels along the cam surface 39 as the platen P moves toward printing position and at the time the platen P moves into a predetermined position relative to the printing device D in printing position, the nose 42 reaches the end of the cam surface 39 and the spring 43 acts to pivot the dog whereby the shoulder 44 thereon moves into the line of movement of the shoulder 45 on the arm 46 unitary with the clamp strip 47 surrounding the eccentric 48 fast on the main drive shaft 12, for at the time the platen P is moving toward printing position the eccentric operates to move the arm 46 outwardly away from the shaft 12. As soon as an impression has been made by the platen P the hooked end portion 49 on the arm 46 engaging a boss 50 on the arm 20 moves the platen P away from printing position into its upper or non-printing position for at this time the eccentric is moving the arm 46 toward the shaft 12. A platen operating mechanism of the foregoing type is preferably employed in the machine because it affords a safety in that printing pressure is not applied to the platen until the time it is in a position so close to the printing

device in printing position that there is not sufficient room for the operator's finger or other obstruction to lie therebelow but while I have described a platen of this character it is to be understood that a platen of any desired type may be employed because the particular type of platen forms no part of the present invention.

Extending across the machine from the magazine M and through and beyond printing position to a printing device receiving galley (not shown) is a printing device guideway 51. Disposed below the guideway 51 is a center bar 52 having a plate 53 on the upper edge thereof on which the printing devices D rest during movement from the magazine through printing position and to the receiving galley, and this plate is preferably of a width equal to the distance between the spacing flanges on the printing devices so that the printing devices will neatly fit on the plate during movement therealong. Extending in juxtaposition to the center bar 52 on each side thereof are rails 54 and 55 and mounted inwardly of the rail 54 is a slide bar 56 having driving pawls 57 mounted thereon which are urged upwardly by springs 58. At the rear end of the slide bar is a shoulder 59 which engages the lowermost of the printing devices in the magazine M and as the slide bar moves toward the left, as viewed in Fig. 1, the lowermost of the printing device is moved from the magazine onto the plate 53. The surface of the slide bar 56 behind the shoulder 59 is in a plane above the remaining portion thereof, and this surface holds the printing devices in the magazine above the lowermost printing device against displacement as the shoulder 59 moves said lowermost printing device onto the plate 53. The slide bar receives a reciprocatory movement and the pawls 57 engage the printing devices during movement of the slide bar to the left in Fig. 1 to advance the printing devices toward printing position and the receiving galley. When the slide bar moves toward the right as viewed in Fig. 1, suitable stop pawls (not shown) engage the printing devices to hold them against movement and the pawls 57 are cammed downwardly against the action of the springs 58 and pass below the printing devices so that when movement of the slide bar to the right is completed each of the pawls will have moved the entire length of one printing device and will have been moved by the springs 58 into engagement with the end of the printing device behind that previously engaged thereby and under which they have just moved.

The slide bar, as has been stated, has a reciprocatory movement imparted thereto. One end of a rod 60 is connected to an arm 61 pivotally connected to the slide bar at 62. The other end of the rod is pivotally connected to the upper end of a rocker 63 mounted on the stub shaft 64 journaled in a portion 65 which is a part of the bracket 24. Another rocker 66 (Fig. 3) is fast on the stub shaft 64 adjacent the rocker 63. On the rear face of the rocker 66 and at the edges are projecting flanges 67 and 68 which provide a trackway 69 therebetween. Disposed in this trackway is a roller 70 carried by the crank 71 mounted at the end of a shaft 72 journaled in the bracket 24. On the shaft 72 is a bevel gear 73 meshing with a bevel gear 74 fast on the main drive shaft 12 and when the main drive shaft 12 is rotated movement is transmitted through the bevel gear 74, bevel gear 73, and shaft 72 to the crank 71 and as the crank 71 rotates the roller 70 reciprocates in the guideway 69 and 75

end of arm 105 and, therefore, the end of arm 105 bearing the screw 108 moves upwardly. This pivots the arm 80 which causes the pin 82 to move along the inclined portion of the pin 83 to disengage the notch 78 from the lug 75 and to thus disconnect the rocker 63 from the rocker 66 which, as previously pointed out, disconnects the printing device feed. The screw 108 is adjustable and, therefore, the amount of movement imparted to the arm 80 may be easily varied. Upon the next operation of the pawl 88, the disc 98 will again be moved one-twelfth of a revolution. It has been pointed out that there are six of the pins 115 and that these pins are equidistantly and circumferentially spaced; therefore, when the first one-twelfth of a revolution was imparted to the disc 98, the disc was rotated in an amount sufficient to dispose the pin 114 midway between two of the pins 115. Thus, when the latter one-twelfth of a revolution is imparted to the disc, the succeeding pin 115 will be moved into engagement with the pin 114 and this will pivot the arm 112 upwardly. A spring 117 extends between the arms 105 and 80 and holds the ends of these arms in engagement with each other. Therefore, when the pin 111 moves upwardly, the end of the arm 105 carrying the screw 108 will move downwardly and the spring 117 will act to reposition the arm 80 in the position illustrated in Fig. 1 and thus the rocker 63 will be reconnected to the rocker 66 and the printing device feed will again function. Should the pawl 88 be aligned with the disc 99 and the pawl then be operated, it will move over the shield 97 and will engage one of the notches of the disc 99 and will impart to said disc one-eighteenth of a revolution. This will disengage one of the pins 115 from the pin 114, and the printing device feed will be disconnected when downward movement of the pin 111 occurs. However, under this condition, the pin 114 will be disposed one-third of the distance between the pins 115 and thus upon the next operation of the pawl 88 the disc 99 will again be moved one-eighteenth of a revolution and the succeeding pin 115 will not engage the pin 114 and, therefore, the printing device feed will again not operate. However, on the next operation of the pawl 88 the disc 99 will again be moved one-eighteenth of a revolution and during this operation the succeeding pin 115 will engage the pin 114 and, therefore, the printing device feed will again be placed in operation. It is therefore apparent that when the pawl 88 is aligned with the disc 98 the printing device feed is interrupted on alternate operations of the machine and when the pawl is aligned with the disc 99 the printing device feed is interrupted for two consecutive operations of the machine and is not reengaged until the third successive operation. Thus, since twenty-four notches are provided in the disc 100, it is apparent that the disc will be rotated but one twenty-fourth of a revolution on each operation of the pawl 88; therefore, when a pin 115 is disengaged from the pin 114 the succeeding pin 115 will not engage the pin 114 until the fourth following operation of the pawl 88. As the pawl 88 is operated with the platen, it controls the operation of the printing device feed and the platen will make consecutive, duplicate, triplicate, or quadruplicate operations on the same printing device depending upon the setting of the pawl 88. To determine the setting of the pawl 88 on the shield 97, I provide the following arrangement: A groove 118 is provided in the shaft 19 through which a rod 119 is extended. One end of the

rod 119 is connected to the bearing portion 90 and the other end is mounted in the bifurcation 120 in the lever 121 (Fig. 6). The lever 121 is fixed on a shaft 122 that is supported at the rear edge of the bed 16. A handle 123 is connected to the shaft 122 and is movable into registration with suitable indices on the upper surface of the bed which indicate the setting, locking means of approved form being provided to retain the handle in registration with different ones of the indices. As best illustrated in Fig. 7, suitable spring washers 124 are disposed between the discs 98, 99, and 100, and these spring washers exert sufficient tension on the discs to prevent turning thereof other than that caused by the pawl 88.

At the time the head H of the selector mechanism moves into the position illustrated in Fig. 2 whereat the fingers F are engaged with the printing device in selector position, the arm 27 is moved into a downward position and the triangularly shaped lug 29 rests on the edge 34 and as has been previously described, when the lug rests on this edge, the arm 22 is so pivoted that the notch 25 is disengaged from the lug 21 so that the platen arm is unlatched. As the platen moves downwardly into printing position, the pawl 88 acts on the disc with which it is aligned, in event said pawl is aligned with one of the discs, and moves the pin 115 from engagement with the pin 114 whereupon the spring 116 pivots the arm 112 in a clockwise direction as viewed in Fig. 2. At the lower end of the arm 112 there is a shoulder 125 and on the arm 27 there is a lug 126 having a flattened face. The pin 115 will disengage the pin 114 at the time the arm 27 is in the position illustrated in Fig. 2, which, as previously stated, is a time at which the triangularly shaped lug 29 is engaging the edge 34 and the fingers F are engaging the printing device in selector position. When the arm 27 is in this position the flat surface on the lug 126 is below the plane of the horizontal portion of the shoulder 125 and consequently, due to the influence of the spring 116, the shoulder will move above the flat surface on the lug 126 and these parts will be held in engagement by the spring 127. Consequently the head H will be held in a position whereat the fingers will remain in engagement with the printing device in selector position and the lug 29 will remain in engagement with the edge 34. In a manner previously described, the feed of the printing devices will have been interrupted and consequently, when the platen returns to its upper or non-printing position, it may immediately start to descend into printing position to make an impression from the printing device from which an impression was previously made for this printing device will remain in printing position. If the device is arranged for making duplicate impressions, the succeeding pin 115 will, upon the second descent of the platen, engage the pin 114, whereby the shoulder 125 will be disengaged from the lug 126. Consequently, the parts may function as determined by the selector mechanism. If the device is arranged for triplicate or quadruplicate impressions, the succeeding pin 115 will not yet engage the pin 114 and hence the shoulder 125 will remain in engagement with the lug 126 and the platen will make another operation so that at least another impression will be made from the printing device in printing position. It is therefore apparent that the multiplier forming the subject matter of this invention not only arranges for repetitious operation 75

of the platen but also renders the selector inoperative until the last of the repetitious impressions is made by the platen.

It is manifest from the foregoing description that I have provided a multiplicator which may be easily set up so that consecutive, duplicate, triplicate, or quadruplicate impressions will be made from the printing devices. The set-up of the multiplicator is determined by a manually movable handle conveniently located in the bed of the machine. Further the multiplicator not only brings about interruption of the feed of the printing devices but likewise releases the platen latching arrangement so that it will not move into latching position until the desired number of impressions have been made. Moreover, the multiplicator renders the selector inoperative in a manner such that the selector again becomes operative and determines the operation of the machine as the last of the repetitious impressions is being made. The device is of simple and economical construction and is efficient and positive in operation and moreover it embodies but a few parts which may be arranged at a convenient location in the machine to thereby facilitate servicing thereof.

In the foregoing description I have illustrated and described a selected embodiment of my invention but it is to be understood that this is capable of variation and modification and I therefore do not wish to be limited to the precise details set forth but desire to avail myself of such changes and alterations as fall within the purview of the following claims:

35 I claim:

1. In a printing machine, a platen, means for sequentially moving printing devices relative to the platen, a plurality of discs, a pawl operable with the platen upon each operative movement thereof and selectively movable into engagement with each of said discs for operating the same, means controlling operative engagement of the pawl with the discs, means for interrupting the printing device movement, and means controlled by said discs for controlling the operation of the movement interrupting means.

2. In a printing machine, a platen, means for sequentially moving printing devices relative to the platen, means for interrupting the movement of said printing devices, a plurality of differently notched discs, means operable with the platen upon each operative movement thereof and selectively engageable with said discs for imparting movement thereto, means controlling operative engagement of the pawl with the discs, and means controlled by movement of said discs for controlling the operation of the printing device movement interrupting means.

3. In a printing machine, a platen, means for moving printing devices through the machine and past the platen, means for interrupting the operation of said printing device moving means, a plurality of differently notched rotatably mounted discs, a pawl operable by the platen and selectively engageable with the discs, a shield over said discs and engaged by said pawl and having portions thereof arranged to control engagement of said pawl with said discs, means for selectively positioning said pawl, and means carried by said discs for regulating the operation of said printing device movement interrupting means.

4. In a printing machine, means sequentially moving printing devices through printing position in the machine and including a movement

transmitting rocker, a driving rocker extending substantially parallel with the movement transmitting rocker, means on said movement transmitting rocker for connecting it to said driving rocker, manually and automatically operable means for disengaging said connecting means whereby said driving rocker may operate independently of said movement transmitting rocker, manually operable means for operating the disconnecting means, and automatically operable means controlling the operation of said disengaging means whereby said disengaging means may be operated to disconnect said driving rocker from said movement transmitting rocker during predetermined operations of said driving rocker.

5. In a printing machine, means sequentially moving printing devices through printing position in the machine, a stub shaft, a movement transmitting rocker mounted on said stub shaft, a driving rocker mounted on said stub shaft adjacent to and in substantially parallel relation with the movement transmitting rocker, said rockers being adapted for similar conjoint movement, a part on the driving rocker extending past the movement transmitting rocker, latch means on said movement transmitting rocker and extending substantially at right angles to the part on said driving rocker and engageable with said part to interconnect said rockers, means controlling the connection of said latch means with said part and including means operable to disconnect the latch means in a predetermined cycle of operation of the machine so that movement of said printing devices through the machine may be interrupted during a predetermined movement of sequential operations of said printing machine.

6. In a printing machine, means sequentially moving printing devices through printing position in the machine and including a movement transmitting rocker, a driving rocker, and means controlling the connection between said movement transmitting rocker and said driving rocker and including a plurality of peripherally notched discs, each of said discs having a different number of notches in the periphery thereof, means selectively engageable with the notches in the periphery of said discs to impart movement thereto, means controlling operative engagement of the pawl discs, and means controlled by the movement of said discs to disconnect and connect said rockers in a predetermined cycle so that the movement of said printing devices through said machine may be interrupted during a predetermined number of sequential operations of said printing machine.

7. In a printing machine, means sequentially moving printing devices through printing position in the machine, an operating member in the machine, operating means for said printing device moving means, controlling means movable in timed relation with said operating member, means regulated by the operation of said controlling means for controlling the operation of said printing device moving means, and means for varying the operation of said controlling means to determine the operation of the means regulated thereby.

8. In a printing machine, means sequentially moving printing devices through printing position in the machine, an operating member in the machine, operating means for said printing device moving means, controlling means including a disc having a plurality of notches in the periphery thereof, circumferentially spaced means in said disc, means cooperating with the circumferentially spaced means in said disc for con-

trolling the operation of said printing device moving means from the operating means therefor, means engageable with said notches for moving said disc, and means controlling operative engagement of the moving means with said notches.

9. In a printing machine, means sequentially moving printing devices through printing position in the machine, an operating member in the machine, operating means for said printing device moving means, controlling means including a disc having circumferentially spaced means therein, said disc having a plurality of notches in the periphery thereof, the number of notches provided in said disc being a multiple of the number of the circumferentially spaced means therein, means cooperating with the circumferentially spaced means in said disc for controlling the operation of said printing device moving means from the operating means therefor, means engageable with said notches for moving said disc, and means controlling operative engagement of the moving means with said notches.

10. In a printing machine, means sequentially moving printing devices through printing position in the machine, an operating member in the machine, operating means for said printing device moving means, controlling means including a pair of discs having circumferentially spaced means extending therebetween, each of said discs having a plurality of notches in the periphery thereof, there being more notches in the periphery of one disc than in the periphery of the other disc, the number of notches in the periphery of said discs being multiples of the number of circumferentially spaced means therein, means cooperating with the circumferentially spaced means in said disc for controlling the operation of said printing device moving means from the operating means therefor, means engageable with said notches for moving said disc, and means controlling operative engagement of the moving means with said notches.

11. In a printing machine, means sequentially moving printing devices through printing position in the machine, an operating member in the machine, operating means for said printing device moving means, controlling means including a disc having circumferentially spaced means therein, said disc having a plurality of notches in the periphery thereof, the number of notches provided in said disc being a multiple of the number of the circumferentially spaced means therein, means operable in timed relation with said operating member and engageable with notches in said disc for imparting movement thereto, means engageable with the circumferentially spaced means in said disc for controlling the operation of said printing device moving means from the operating means therefor, and means regulating the operative engagement of the means engageable with the notches in said disc.

12. In a printing machine, means sequentially moving printing devices through printing position in the machine, an operating member in the machine, operating means for said printing device moving means, controlling means including a pair of discs having circumferentially spaced means extending therebetween, each of said discs having a plurality of notches in the periphery thereof, there being more notches in the periphery of one disc than in the periphery of the other disc, the number of notches in the periphery of said discs being multiples of the num-

ber of circumferentially spaced means therein, means operable in timed relation with the said operating member and selectively engageable with either of said discs whereby movement will be imparted to said discs in accordance with the spacing of the notches in the periphery thereof, and means engageable with the circumferentially spaced means in said disc for controlling the operation of said printing device moving means from the operating means therefor.

13. In a printing machine, means sequentially moving printing devices through printing position in the machine, an operating member in the machine, operating means for said printing device moving means, controlling means including a plurality of discs having circumferentially spaced means extending therebetween, said discs having notches in the periphery thereof, each of said discs having a different number of notches, the number of notches in each of said discs being a multiple of the number of circumferentially spaced means extending between said discs, means operable in timed relation with said operating member and selectively engageable with said discs for imparting movement thereto in correspondence with the number of notches therein, and means engageable with the circumferentially spaced means in said disc for controlling the operation of said printing device moving means from the operating means therefor.

14. In a printing machine, means sequentially moving printing devices through printing position in the machine, an operating member in the machine, operating means for said printing device moving means, controlling means including a pair of discs having circumferentially spaced means extending therebetween, each of said discs having a plurality of notches in the periphery thereof, there being more notches in the periphery of one disc than in the periphery of the other disc, the number of notches in the periphery of said discs being multiples of the number of circumferentially spaced means therein, a shield arranged over said discs and having the portion thereof in alignment with the disc having the least notches therein cut away to a greater extent than the portion thereof aligned with the disc having the greater number of notches therein is cut away, and means operable in timed relation with said operating member and engaged with said shield whereby said means may move from engagement with said shield and into engagement with one of said discs to impart movement thereto in correspondence with the spacing of the notches in the periphery thereof, and means engageable with the circumferentially spaced means in said disc for controlling the operation of said printing device moving means from the operating means therefor.

15. In a printing machine, means sequentially moving printing devices through printing position in the machine, an operating member in the machine, operating means for said printing device moving means, controlling means including a plurality of discs having circumferentially spaced means extending therebetween, said discs having notches in the periphery thereof, each of said discs having a different number of notches, the number of notches in each of said discs being a multiple of the number of circumferentially spaced means extending between said discs, a shield extending over said discs and having the portion in alignment with the disc having the least number of notches therein cut away to a

- greater extent than the portion thereof aligned with the disc having the greater number of notches therein is cut away, the portions of said shield aligned with other of said discs being cut away in an amount intermediate the cutting away thereof of the portions aligned with the discs having a greater and less number of notches than the disc with which the respective portion of the shield is aligned, means operable in timed relation with said operating member and engaged with said shield whereby said means may move from engagement with said shield and into engagement with one of said discs to impart movement thereto in correspondence with the spacing of the notches in the periphery thereof, and means engageable with the circumferentially spaced means in said disc for controlling the operation of said printing device moving means from the operating means therefor.
20. A control device adapted for use in a printing machine of the like and including a plurality of independently movable discs arranged at spaced intervals along a shaft, said control member having notches in the periphery thereof, the number of notches in each of said discs being different, regulating means comprising pins extending through all of said discs substantially parallel to said shaft and in spaced relation with each other, the number of notches in the periphery in each of said discs being a multiple of the number of pins arranged therein. 5
21. A control device adapted for use in a printing machine or the like and including a plurality of independently movable discs arranged at spaced intervals along a shaft, said control member having notches in the periphery thereof, the number of notches in each of said discs being different, regulating means comprising pins extending through all of said discs substantially parallel to said shaft and in spaced relation with each other, the number of notches in one of said discs being equal to the number of pins extended through said discs, the number of notches in the other of said discs being an even multiple 10 of the number of pins.
22. A control device adapted for use in a printing machine or the like and including a disc having regulating means extending transversely thereof intermediate the periphery and the center 15 of said disc, said disc having notches in the periphery thereof, the number of notches in the periphery of said disc being a multiple of the number of regulating means therein, and means engageable in said notches for imparting movement to 20 said disc, and means controlling the operative engagement of the movement imparting means with said notches.
23. A control device adapted for use in a printing machine or the like and including a plurality of discs having regulating means arranged at spaced intervals therein, said discs having notches in the peripheries thereof, the number of notches in the peripheries of said discs being a multiple 30 of the number of regulating means therein, means 35 selectively engageable with the notches in said discs for imparting movement to said discs, and means controlling the engagement of the movement imparting means with said notches to regulate the engagement of said means with said 40 notches in accordance with the number of notches in the peripheries of the discs.
24. A control device adapted for use in a printing machine or the like and including a plurality of discs having regulating means arranged at spaced intervals therein, said discs having notches in the peripheries thereof, the number of notches in the peripheries of said discs being a multiple 45 of the number of regulating means therein, means selectively engageable with the notches in said discs for imparting movement to said discs, and means controlling the engagement of the movement imparting means with said notches to regulate the engagement of said means with said 50 notches in accordance with the number of notches in the peripheries of the discs.
25. A control device adapted for use in a printing machine or the like and including a plurality of independently movable discs mounted at spaced intervals along a shaft, said discs having movement receiving means thereon, and regulating means passed through said discs and providing regulating positions intermediate said discs, the number of movement receiving means on said discs being a multiple of the number of regulating means passed through said discs. 55
26. A control device adapted for use in a printing machine or the like and including a plurality of independently movable discs mounted at spaced intervals along a shaft, said discs having movement receiving means thereon, and regulating means passed through said discs and providing regulating positions intermediate said discs, the number of movement receiving means on one of said discs being equal to the number of regulating means passed through said discs, the number of movement receiving means on the other of said discs being an even multiple of the 60 number of said regulating means.
27. A control device adapted for use in a printing machine or the like and including a disc having regulating means extending transversely thereof intermediate the periphery and the center of said disc, said disc having notches in the periphery thereof, the number of notches in the periphery of said disc being a multiple of the number of regulating means therein, means selectively engageable with the notches in said discs for imparting movement to said discs, and means controlling the engagement of the movement imparting means with said notches to regulate the engagement of said means with said notches in accordance with the number of notches in the peripheries of the discs. 65
28. A control device adapted for use in a printing machine or the like and including a plurality of discs having regulating means arranged at spaced intervals therein, said discs having notches in the peripheries thereof, the number of notches in the peripheries of said discs being a multiple of the number of regulating means therein, means selectively engageable with the notches in said discs for imparting movement to said discs, and means controlling the engagement of the movement imparting means with said notches to regulate the engagement of said means with said notches in accordance with the number of notches in the peripheries of the discs, the means controlling the engagement of the movement imparting means with the notches in said discs including a part with which the movement imparting means may be selectively registered, said part serving to prevent the movement imparting means for engaging the notches in said discs and imparting movement to said discs. 70
